UNITED STATES PATENT OFFICE.

EMIL A. ERICKSON, OF CANBY, MINNESOTA.

STOOL FOR LUNCH COUNTERS.

Application filed February 4, 1927. Serial No. 165,871.

This invention relates to a stool or chair and especially to a stool or chair used in connection with a counter such as a lunch counter. It is now a common practice to have stools or chairs arranged along the lunch counter which the patrons occupy when being served at the counter. As the people vary greatly in size, when a stool is arranged to be comfortable for one person, it will not be comfortable for another. Some people prefer to have the stool close to the counter and others prefer to have it at some distance from the counter. It is desirable, therefore, to have a stool or chair which is movable to different positions to suit the convenience and size of the individual using the same.

It is an object of this invention, therefore, to provide a stool or chair for a lunch counter which is movable in relation to the counter to suit different individuals.

It is a further object of the invention to provide a stool or chair for a lunch counter having a base which is held in fixed position and having a seat portion which is movable towards and from the counter.

It is more specifically an object of the invention to provide a stool or chair for a lunch counter having a base fixed to the floor and a standard rising therefrom and having a seat portion which is slideable in said standard portion and from said counter, and which also preferably has guiding means in said standard.

These and other objects and advantages of the invention will be fully set forth in the following description made in connection with the accompanying drawings, in which like reference characters refer to similar parts throughout the several views and in which:—

Fig. 1 is a view in side elevation of the stool, a portion of the counter being shown in vertical section;

Fig. 2 is a horizontal section taken on line 2—2 of Fig. 1, as indicated by the arrows; and

Fig. 3 is a vertical section taken on line 3—3 of Fig. 1 as indicated by the arrows.

Referring to the drawings, in Fig. 1 a portion of a counter is shown having the front side 5 and the top 6. A stool is provided having a base member 7 shown as circular in form and secured to the floor or other supporting surface 8 by the screws 7^b. The base portion 7 has a central upstanding hub 7^a in which is secured the standard 9 which rises from said base member. The standard 9 is somewhat enlarged at its top and has a slot

9^a extending therethrough in a direction substantially at right angles to the front side of the counter. The standard is also provided with a hole 9^b extending therethrough in the same direction as the slot 9^a and some distance below said slot. A seat or top 10 is provided for the stool, which preferably will be of wood or similar material and circular in shape, as shown. The seat 10 has a bracket 11 secured to its under side, having laterally extending flanges engaging the bottom of said seat and secured thereto by the screws 12. The standard 11 is substantially of U-shape and has a portion 11^b projecting from the flanges 11^a which is rectangular in cross section and substantially fits in the groove 9^a. The bracket 11 also has a cylindrical lower arm 11^c extending parallel to the portion 11^b which extends through and substantially fits in the hole 9^b. The portions 11^b and 11^c are connected by the end piece 11^d. The portions 11^b and 11^c have flat ends disposed in the same plane and a plate 13 extends between said ends and is secured thereto by the screws 14. With the structure described, it is seen that the seat or top 10 can be moved toward and from the counter and the same disposed in various positions as shown by the dotted lines in Fig. 1. The stool can thus be moved closer to the counter or farther therefrom. It will be seen that the portion 11^b slides in the slot 9^a and the portion 11^c slides in the hole 9^b. The top is thus firmly held in position and has little or no tendency to move after once being adjusted. The portions 11^b and 11^c, when a person is sitting on the stool, tend to bind in their respective seats, so that the top is not easily moved.

In operation the stool will be disposed at the side of the counter as shown in Fig. 1. The person desiring to sit at the counter will quickly slide the seat 10 so as to place the same in a comfortable position. After the person is seated on the stool as above stated, the top has little or no tendency to move and the same will thus be disposed in the position which is the most comfortable and convenient for the occupant.

From the above description it is seen that applicant has provided a very simple and efficient structure of stool or chair and one especially adapted for use with lunch counters. The device is easily and inexpensively made and comprises few extra parts over the ordinary stationary stool. The device has

been amply demonstrated in actual practice and found to be very successful and efficient.

It will, of course, be understood that various changes may be made in the form, details, arrangement and proportions of the parts, without departing from the scope of applicant's invention, which, generally stated, consists in a device capable of carrying out the objects above set forth, in the novel parts and combinations of parts disclosed and defined in the appended claims.

What is claimed is:—

1. A stool or chair having a base, a standard rising from said base, said standard having a slot extending transversely thereof at its upper end and having an aperture therethrough beneath said slot, a seat portion having means secured to its under surface fitting in and slideable in said slot forming a guide, said means also comprising a portion slideable in said aperture.
2. A stool or chair having in combination, a seat, a bracket secured to the under side of said seat having upper and lower horizontal bars, said upper bar being angular in vertical cross section, a support having a base

adapted to be secured to the floor and having a standard upstanding from said base, said standard having a slot in its upper end in which said upper bar fits to form a guiding means, said standard having an aperture therethrough below said slot through which said lower bar passes, said bars being slideable in said slot and aperture respectively, and means on said bracket limiting the sliding movement of said bars and seat.

3. A stool or chair having in combination, a base adapted to be secured to a support, a standard rising from said base having a recess extending transversely of its upper surface and having a hole therethrough a short distance below said recess, a seat having a member secured to the under side thereof and extending transversely thereof, said member fitting in said recess of said standard and slideable therein, and additional guiding means for said seat comprising a rod carried by said member, which rod extends through and is slideable in said hole in said standard.

In testimony whereof I affix my signature
EMIL A. ERICKSON.
